(57) **CLAIM**

The ornamental design for a surgical illuminator, as shown and described.

DESCRIPTION

FIG. 1 is a first isometric view of a surgical illuminator drawn broken away to indicate indeterminate length, showing our new design;

FIG. 2 is a second isometric view thereof;

FIG. 3 shown slightly reduced in scale is a front view thereof;

FIG. 4 is a partial side view looking in the direction indicated by line 4—4 in FIG. 3; and,

FIG. 5 is a partial side view looking in the direction indicated by line 5—5 in FIG. 3.

The broken lines showing of the controls are included for the purpose of illustration and forms no part of the claimed design.
